UNITED STATES PATENT OFFICE.

CHARLES H. BOMBARDIE, OF CHICAGO, ILLINOIS, ASSIGNOR TO WIREBOUNDS PATENTS COMPANY, A CORPORATION OF MAINE.

MACHINE FOR USE IN MAKING BOXES.

Application filed April 15, 1921. Serial No. 461,536.

To all whom it may concern:

Be it known that I, CHARLES H. BOMBARDIE, a citizen of the United States, and a resident of Chicago, in the county of Cook and State of Illinois, have invented an Improvement in Machines for Use in Making Boxes, of which the following is a specification.

The invention relates to machines for use 10 in making boxes, box blanks or parts thereof, and, among other objects, is intended to provide a machine of the class described having improved means for positioning the work.

15 One illustrative form of machine embodying the invention is shown in the accompanying drawings, in which:

Fig. 1 is a side elevation of one type of wire bound box blank machine embodying 20 the invention;

Fig. 2 is an enlarged cross section of one of the work-forwarding chains and its support showing the work-positioning means, said section being taken on the line A—A 25 of Fig. 1;

Fig. 3 is an enlarged side elevation of one of the work-forwarding chains and its support seen from B—B in Fig. 2.

The illustrative machine is of the type 30 disclosed in the Reissue Letters Patent to O. C. Thompson, No. 15,045, issued February 15, 1921, and consists generally of a gang of staplers 1 adapted to form staples from wire fed thereto and drive the staples 35 over binding wire into box parts progressively subjected to the action thereof. The box parts are assembled on endless conveyer chains 2 travelling in channel guides 3 on the supports 4 and are trained over sprocket 40 wheels 5 and 6 respectively at either end of the machine. The work-forwarding chains 2 are advanced intermittently by a ratchet and pawl mechanism 7.

In the manufacture of wire bound boxes, 45 the materials are assembled on the work-forwarding chains 2 and are spaced apart the desired distance by means of spacer blocks 8 which may be adjustably secured to a flange 9 of the work-forwarding chains. 50 Thus in the manufacture of a four sided box, five spacer blocks 8 are used for each box assembly, one at either end of the box assembly and the other three between sections thereof. The endless work forward- 55 ing chains are usually of a length to accommo-

date from six to eight box assemblies depending upon the size of the box desired although said chains may be lengthened or shortened to accommodate a greater or lesser number of box assemblies. It is desirable that the blocks 8 on either work-forwarding chain 2 be in exact alignment one with the other to properly position the materials for each section of a box assembly and it is also desirable that each group of 60 spacer blocks 8 be positioned alike in order to produce boxes of uniform size and spacing. Applicant has therefore provided positioning means for aligning the spacer blocks on the two parallel work-forwarding 65 chains and which enables the operator to effect a like positioning and spacing of materials for a succession of box assemblies.

Referring to Figs. 2 and 3, the positioning means comprises a series of positioning 70 members 10 at either side of the machine, adjustably clamped to a shaft 11 by means of screws 12, said shaft 11 being adapted to revolve in brackets 13 secured to the support 4 by screws 14. Shafts 11 are provided at both sides of the machine and extend from a short distance in front of the 75 staplers 1 parallel with the supports 4 to the front end of the machine. The brackets 13 nearest the staplers and the brackets 13 80 at the forward end of the machine are preferably fixed while the intermediate brackets are slidably within certain limits to accommodate the positioning members 10. The positioning members 10 which lie nearest 85 the staplers at either side of the machine are also preferably in fixed alignment one with the other so that the first spacer blocks 8 for each box blank may be positioned in exact alignment. The intermediate positioning members 10 are adjusted the proper 90 distances from the fixed members and from each other on shafts 11 and clamped to said shafts by the screws 12. Spacer blocks 8 are then clamped to the work-forwarding 95 chains at the points determined by the positioning members 10 as shown in Fig. 3. After the spacer blocks 8 for one box assembly have thus been positioned, the positioning members 10 are swung back out 100 of engagement with the work-forwarding chains and said chains are then advanced until the last spacer block 8 has passed the first positioning member 10. The patterns 105 of positioning members 10 are then swung 110

back into position against the work-forwarding chains 2 and a spacer block 8 is secured to the work-forwarding chains adjacent each positioning member 10 thus positioning the second group of spacer blocks to correspond with the first. This operation is repeated until all of the groups of spacer blocks have been properly positioned on the work-forwarding chains. The positioning members 10 are then swung outward and downward where they remain until a new set-up of the chain is required for a different sized box.

Thus it will be noted that a pattern mechanism has been provided for positioning a spacer block or a group of spacer blocks on one work-forwarding chain in exact alignment with another spacer block or group of spacer blocks on a parallel chain, and which is adapted to effect the same positioning of a succession of blocks or groups of blocks.

This is particularly advantageous because it insures the exact alignment of the spacers on the two work-forwarding chains thus correctly and accurately positioning and spacing the several sections of a box assembly and insures uniformity in the product of the machine. Another advantage is that considerable time is saved in setting up the machine each time a different sized box is to be made because the pattern of positioning members will position a succession of groups of spacer blocks according to the pattern thus eliminating the independent set up of each group of spacer blocks. Another advantage is that with applicant's device unskilled labor may be employed to set up the machine after the pattern of positioning members is once set up.

Heretofore in setting up the spacer blocks on the work-forwarding chains the operator first had to adjust the first blocks of the first group of blocks as nearly in alignment as he was able to place them and then measure off the required distances of each succeeding block of each succeeding group of blocks all around the work-forwarding chains. This was a long and laborious operation and very often resulted in improper alignment of the blocks. In applicant's machine the positioning members for the first spacer block are fixed in exact alignment so that it is impossible for the first blocks to be out of line. With the first positioning members in exact alignment it is a simple matter to locate the succeeding members for a box assembly the proper distances therefrom. With the pattern of positioning members thus properly set for one box assembly all the groups of spacer blocks on the work-forwarding chains may be quickly and accurately set in accordance with the pattern.

It will be understood that the illustrative box blank machine is only one of several types and that applicant's invention is susceptible of embodiment in machines of other types and in various combinations and sub-combinations. 70

Having described the invention what is claimed is:

1. A machine for use in making boxes comprising, in combination, work-forwarding means including box part positioning members; binding-wire-applying mechanism; and means to control the location of said positioning members to position a group of box parts in predetermined spaced relationship on said work-forwarding means, said controlling members being adapted to control a succession of groups of positioning members to position a succession of groups of box parts in like spaced relationship. 75 80 85

2. A machine for use in making boxes comprising, in combination, work-forwarding means comprising parallel conveyers having adjustable members for positioning box parts thereon; binding-wire-applying mechanism; and means to align a group of spaced positioning members on one conveyer opposite a similarly spaced group of positioning members on the other conveyer, 90 95 said means being adapted to similarly align a succession of such groups.

3. A machine for use in making boxes comprising, in combination, work-forwarding means; binding-wire-applying mechanism; adjustable members to position box parts on the work-forwarding means; and pattern means to control the position of a group of said positioning members in desired relationship on the work-forwarding means, said pattern means being adapted to position a succession of such groups in like relationship. 100 105

4. In a machine for use in making boxes, the combination of work-forwarding means comprising parallel conveyers each having a series of members adjustably spaced thereon for positioning a series of box parts and means to control the spaced relationship of said positioning members. 110 115

5. In a machine for use in making boxes, the combination of work-forwarding means comprising parallel conveyers each having a plurality of series of members adjustably spaced thereon for positioning a plurality of series of box parts and means to control the spaced relationship of said positioning members whereby each series thereof will be similarly spaced. 120 125

6. In a machine for use in making boxes, the combination of work-forwarding means comprising parallel conveyers each having a series of members adjustably spaced thereon for positioning a series of box parts and means to control the spaced relationship of 130

- said positioning members whereby the positioning members on said conveyers will be in like spaced relationship and in transverse alignment.
- 5 7. In a machine of the class described having a pair of parallel conveyers provided with adjustable members for positioning box parts thereon, pattern means for positioning in spaced relationship a series of adjustable members along one of said conveyers and similar pattern means for effecting a like disposition of adjustable members along the other conveyer.
- 10 8. In a machine of the class described having a pair of parallel conveyers provided with adjustable members for positioning box parts thereon, pattern means for positioning in spaced relationship a series of adjustable members along one of said conveyers and similar pattern means for effecting a like disposition of adjustable members along the
- other conveyer and in direct transverse alignment with the adjustable members on the first conveyer.
9. In a machine for making box blanks by attaching binding wire to a plurality of sections of box materials, the combination of endless work-conveyer chains, blocks adjustably secured thereon to position the several sections of a box blank, and means to position said blocks in proper spaced relationship on said chains comprising a pattern of positioning members pivoted to the machine and adapted to be swung into contact with a conveyer chain to locate the positions of the work-positioning blocks and to be swung out of the path of travel of said blocks after they have been positioned.
- 15 20
- In testimony whereof, I have signed my name to this specification.

CHARLES H. BOMBARDIE.
